UNITED STATES PATENT OFFICE

152,057

DESIGN FOR A SWEATER

Betty Ann Bryce, Tacoma, Wash., now by decree of marriage Betty Ann Dobiash

Application July 30, 1946, Serial No. 132,100

Term of patent 7 years

(Cl. D3—4)

To all whom it may concern:

Be it known that I, Betty Ann Bryce, a citizen of the United States of America, residing at Tacoma, county of Pierce, State of Washington, have invented a new, original, and ornamental Design for Sweaters, of which the following is a specification, reference being had to the accompanying drawing, forming part thereof.

The figure is a front view of a sweater, showing my new design.

The sleeves and the back of the sweater are plain.

I claim:

The ornamental design for a sweater, as shown and described.

BETTY ANN BRYCE.
